UNITED STATES PATENT OFFICE.

AUGUST TANNER, OF BROOKFIELD, MISSOURI.

MORTISE-LOCK.

936,185.

Specification of Letters Patent.

Patented Oct. 5, 1909.

Application filed October 8, 1907. Serial No. 396,460.

To all whom it may concern:

Be it known that I, AUGUST TANNER, a citizen of the United States, residing at Brookfield, in the county of Linn and State 5 of Missouri, have invented new and useful Improvements in Mortise-Locks, of which the following is a specification.

This invention relates to locks, the main object of the present invention being to provide a secure lock which is as far as possible 10 burglar proof and which has the parts thereof so constructed and arranged as to prevent an unauthorized person from tampering therewith by removing portions of the lock 15 to gain access to other parts thereof.

A further object of the invention is to provide a combined latch and lock in connection with means independent of the key 20 for holding the locking bolt against movement.

With the above and other objects in view, the nature of which will more fully appear as the description proceeds, the invention 25 consists in the novel construction, combination and arrangement of parts hereinafter fully described, illustrated and claimed.

In the accompanying drawings: Figure 1 is an elevation of the lock looking from the outside of the door. Fig. 2 is an elevation 30 of the lock looking from the inside of the door. Fig. 3 is a sectional plan view of the lock. Fig. 4 is an elevation of the lock with the adjacent face plate of the lock case removed. Fig. 5 is a detail sectional view of 35 the bolt, showing the relation of the yoke thereto. Fig. 6 is a detail perspective view of the reversible lip or nose of the bolt. Fig. 7 is a similar view of the tumbler head or carrier and the tumblers carried thereby. Fig. 8 is a detail perspective view of the 40 knob lock. Fig. 9 is a detail section through the knob lock taken on the line 9—9 of Fig. 3.

The lock contemplated in this invention comprises a lock case 1 of suitable size to 45 receive the lock mechanism hereinafter described, said lock case being provided at one end with a face plate 2 having an opening through which the lip or nose of the bolt passes.

The bolt 3 is substantially L-shaped as 50 shown in Figs. 4 and 5 and is provided with a socket 4 in which the shank 5 of the lip or nose 6 of the bolt is secured by means of a pin, screw or other suitable fastening 7, by 55 the removal of which the nose or lip 6 may be reversed so as to bring the inclined face

8 thereof toward either side of the lock, thus adapting the lock as a whole to be used either right hand or left hand.

The inner end of the bolt is recessed as 60 shown at 9 to receive and admit of the movement of a bolt throwing arm 10 which projects from a yoke 11 which in the main is of the usual form, being provided with a squared hole 12 for the knob shank 13 so that when 65 either of the knobs is turned the arm 10 operates to slide the bolt back and forth, the bolt being normally held outward in locking position by means of a two armed spring 14 arranged in the inner lower corner of the 70 lock case as shown in Fig. 4, one arm of said spring bearing against a cam shoulder 15 on the yoke 11. The cam shoulder 15 is preferably provided with an anti-friction roller 16 which bears directly against the 75 spring 14 thus reducing the friction to a minimum.

17 designates a pair of fixed guide lugs within the lock case against which the sliding bolt 3 moves.

Arranged at the opposite side of the guide lugs 17 is a tumbler head or carrier 18 having a reduced shank 19 on opposite sides of which are arranged tumblers 20 all mounted on a common pivot 21 by which they are 85 connected to the tumbler head or carrier. The tumbler head slides in a direction parallel with the movement of the bolt 3 between the lugs 17 and an oppositely arranged guide lug 22 while another stop lug 23 90

is provided with which the tumblers interlock as shown in Fig. 4, the lug 23 also serving as a guide lug for the tumbler head 18. Two pivoted tumblers 20 are shown on each side of the shank 19 of the tumbler head but 95 the number of pivoted tumblers may be increased or diminished at will. Each tumbler is provided with a substantially semi-circular key-way 24 in which the bits of the key work and is also provided with shoulders 25 100 and 26 between which the stop lug 23 is received for holding the tumblers and preventing longitudinal movement of the tumbler head. Each tumbler is furthermore recessed in its upper portion as shown at 27 and with 105 in such recess is arranged a tumbler depressing spring 28 which rides against one of the guide lugs 17 above referred to, said spring acting to hold the tumbler in engagement with the stop lug 23.

When, by means of the key, the tumblers 110 are moved out of engagement with the stop

lug 23, the tumbler head is slid backward by the key until the inner end of the tumbler moves against a stop shoulder 29 on the yoke 11. This prevents the yoke from being turned by the knob spindle and therefore holds all parts of the lock against any movement whatever. To release the several parts of the lock mechanism, the tumbler head together with the tumblers carried thereby must be shifted away from the knob spindle so as to disengage the tumbler head from the stop shoulder 29 after which the knobs may be turned to shift the bolt.

In the preferred embodiment of this invention, the knobs 30 and 31 at the outside of the door constitute short levers by projecting wholly to one side of the axis of the knob spindle as clearly shown in Fig. 3, and in order to prevent a person on the outside of the door from removing the usual screw 32 which fastens the hub 33 of the knob to the spindle 13, I employ a guard sleeve 34 which slips over the spindle and entirely incloses and protects the screw 32 said sleeve being confined between the knob and lock case. The knob 31 at the inner side of the door is likewise provided with a hub 35 fastened to the knob spindle by means of the usual screw 36. The hub 35 is provided with a fixed collar 37 from which extends an arm 38 provided at its outer end with a sleeve 39 in which is slidably fitted the plunger 40 of a knob lock having at its outer end a head or button 41 by means of which it may be pushed inward or drawn outward. The plunger 40 is provided in one side with a notch 42 which is engaged by the lip or tooth 43 of a spring detent 44 secured to and carried by the arm 38, as shown in Fig. 9, the lip 43 being adapted to snap into the notch 42 to hold the plunger of the knob lock when thrust inward. The escutcheon plate 45 at the inner side of the door is provided with a hole or socket to receive the inner end of the knob lock plunger 40; and it will now be seen that when the door is closed and the bolt in engagement with the keeper, by pushing the knob lock plunger inward, it interlocks with the escutcheon plate at the inner side of the door and prevents the knobs from being turned.

The keeper or striking plate 47 is composed of a piece of sheet metal secured to the door

jamb or frame by ordinary wood screws, the greater number of which are covered by the door stop 48 which is applied to the door frame after the keeper is secured in place. The forward edge of the keeper is bent over or curved to one side as shown at 49 to facilitate coöperation with the lip or nose of the bolt in the act of closing the door. This also obviates the objectionable projection of the lip of the keeper now in common use and avoids catching the clothing thereon when passing hurriedly through the door.

In order to still further guard against fraudulent entry, reinforcing strips 50 of metal are secured to the door on the outside and inside and adjacent to the free edge of the door as shown in Figs. 1 and 2, and these strips are held in place by suitable fastenings, which, if in the form of screws, are preferably headed on the outside to prevent the removal of the outside strip by an unauthorized person. The knob levers 30 and 31 are arranged to turn away from the door jamb so as to avoid getting the fingers caught and hurt in opening and closing the door.

Having thus fully described the invention, what is claimed as new is:—

A lock comprising a case, a sliding bolt, a knob spindle, a spindle hub provided with a bolt throwing arm, a radial shoulder projecting from said hub, a sliding tumbler head movable in a rectilinear path at one side of and parallel to the plane of movement of the bolt and shiftable into and out of interlocked engagement with the radial shoulder on the spindle hub, a plurality of tumblers arranged at opposite sides of said head and having a common pivotal connection with the same, individual springs carried by said tumblers and movable in sliding contact with a fixed surface, a projection on the spindle hub, and a flat spring bearing against said projection and operating to turn said hub and throw the bolt outward.

In testimony whereof I affix my signature in presence of two witnesses.

AUGUST TANNER.
